UNITED STATES PATENT OFFICE.

WILLIAM MARTIN, OF GLOVERSVILLE, NEW YORK.

OVERCOAT.

No. 918,878.

Specification of Letters Patent.

Patented April 20, 1909.

Application filed October 14, 1908. Serial No. 457,706.

To all whom it may concern:

Be it known that I, WILLIAM MARTIN, a citizen of the United States, residing at Gloversville, in the county of Fulton and

5 State of New York, have invented certain new and useful Improvements in Overcoats; and I do hereby declare the following to be a full, clear, and exact description of the invention, such as will enable others skilled in the 10 art to which it appertains to make and use the same, reference being had to the accompanying drawings, and to the letters of reference marked thereon, which form a part of this specification.

15 This invention relates to new and useful improvements in overcoats and especially to fur coats designed for use in automobiling, horseback riding, etc.

More specifically, the invention consists of 20 an overcoat having slits or vents in the lower edge thereof forming a plurality of flaps, the outer of which are adapted to be brought about the leg of the wearer and the edges fastened together, while the intermediate flap 25 forms a skirt upon which the person wearing the coat may sit when riding or driving.

An essential feature of the present invention consists in the formation of the coat in such a manner that, when it is not desired to 30 fasten the outer flaps about the leg of the person wearing the coat, the flaps may be brought together edge to edge and fastened, thus giving the appearance of a continuous skirted coat.

35 The invention comprises various details of construction, combinations and arrangements of parts which will be hereinafter fully described and then specifically defined in the appended claim.

40 My invention is illustrated in the accompanying drawings, in which:—

Figure 1 is a perspective view showing the coat with the flaps fastened together forming a continuous skirt. Fig. 2 is a similar view 45 showing the outer flaps disconnected from the central flap and brought about the legs of a wearer and fastened together. Fig. 3 is a rear elevation of the coat showing the flaps fastened together, giving the coat the appearance of a continuous skirt. Fig. 4 is a rear elevation of Fig. 2, showing the intermediate flap hanging loosely while the outer flaps are fastened together about the legs of the wearer. Fig. 5 is a diagrammatic view 55 showing the manner in which the meeting

edges of the flaps are fastened together when the coat is adjusted to have the appearance of a continuous skirt. Fig. 6 is a diagrammatic view showing the manner in which the outer flaps are brought together about the 60 legs of a wearer and secured edge to edge, and Fig. 7 is an enlarged detail view showing the manner of the meeting of the edges of the flaps when brought together.

Reference now being had to the details of the drawings by letter, A designates a coat, the skirt of which is provided with two slits or vents B, dividing the skirt into three flaps, designated respectively by letters C, D and E and upon the central flap C are the eye plates H and upon the adjacent edge of the flaps E are the spring-actuated pivotal tongues K adapted to be inserted through said plates H, whereby the meeting edges of the flaps may be held in contact with each other and not overlap, as shown clearly in the drawings, especially in Fig. 7, so that the outer surface of the coat will give the appearance of a continuous skirt, the hairs which are preferably of a curly nature intermingling with one another and thus completely hiding the seam. When it is desired to utilize the coat in the manner shown in Figs. 2 and 4 of the drawings for the purpose of causing the outer flaps to fold about the legs of a person, the fastening means shown in Fig. 1 of the drawings are detached and the two outer flaps brought one about each leg and the fastening means adjusted in the manner shown in Fig. 2, so that the meeting edges 70 of each outer flap are brought together and securely held, thus protecting the legs of the wearer of the coat.

It will be noted that the slits which are formed in the bottom of the coat are parallel to each other, so that the intermediate and side flaps formed thereby, when fastened together in the manner shown in Fig. 3 of the drawings, have the appearance of a coat with a continuous undivided skirt. The 75 meeting edges in this adjustment do not overlap each other but the inner and outer faces of the coat are flush and, when the coat is made of a fur, for which this construction is especially adapted, there is no visible slit 80 apparent from the outside. When the outside flaps are brought together in the manner shown in Fig. 2 of the drawings, the opposite parallel edges of said side flaps are brought 85 edge to edge without overlapping, while the 90

intermediate flap C hangs in its normal condition and forms a seat upon which the person may sit when riding or driving.

What I claim to be new is:—

5 An overcoat having slits formed in its lower edge dividing the skirt into an intermediate and two side flaps, the rear edges of the side flaps being parallel with the two edges of the intermediate flap, the side flaps
10 being adapted to be joined to the edges of

the intermediate flap with their edges abutting those of the intermediate flap without overlapping, as shown and described.

In testimony whereof I hereunto affix my signature in the presence of two witnesses. 15

WILLIAM MARTIN.
